UNITED STATES PATENT OFFICE.

FREDERICK J. FRENZ, OF ALLISON PARK, PENNSYLVANIA.

BOILER.

1,089,918.

Specification of Letters Patent. Patented Mar. 10, 1914.

Application filed February 27, 1913. Serial No. 751,040.

To all whom it may concern:

Be it known that I, FREDERICK J. FRENZ, a citizen of the United States, residing at Allison Park, in the county of Allegheny and State of Pennsylvania, have invented certain new and useful Improvements in Boilers, of which the following is a specification.

My invention consists of an improvement 10 in boilers and is designed to provide a boiler construction particularly adapted for hot water heating systems, where a moderate degree of heat and steam pressure is desired.

The invention has in view to provide a 15 boiler of this type composed entirely of metal having a casing or shell structure of hollow cast metal end and side walls providing interior circulation cavities, circulating water tubes connected with the inner 20 partition walls of the main front and back walls, and establishing circulation between the cavities thereof, hollow cast metal headers having circulating communication with some of the tubes and said cavities, and also 25 constituting baffling or circulation controlling partitions, fuel and combustion chambers, tubular connections, etc., the several parts being arranged and connected and comprising various detail features of construction and advantage, as shall be more 30 fully hereinafter described.

In the drawings which show preferred forms of the invention,—Figure 1 is a view partly in front elevation and partly in section showing at the middle portion the construction in section indicated by the line I. I., and at the right hand portion the construction in section indicated by the line I^a. I^a of Fig. 2. Fig. 2 is a central vertical sectional view, indicated by the line II. II. of Fig. 1. Fig. 3 is a partial horizontal sectional view indicated by the line III. III. of Fig. 2. Fig. 4 is a central vertical sectional view, generally similar to Fig. 2, 45 showing a modified arrangement of the combustion chamber. Fig. 5 is a partial similar view showing the adaptation of the boiler to the use of gaseous fuel. Fig. 6 is a cross sectional view of the upper portion of 50 the boiler, similar to Fig. 1, but showing the boiler provided with a steam drum at the top. Fig. 7 is a view partly in side elevation and partly in section of the construction of Fig. 6, indicated by the section line VII. VII. thereof.

The front wall A, the back wall B and

the side walls C. C. of the boiler, are of hollow cast framework, each having an inner wall 2 and an outer wall 3 providing intervening water circulation spaces a, b, and c, respectively, each of said castings having bottom and top closing walls 4, 5, respectively forming with the walls 2 and 3 containing chambers or boxes. The inner and outer web portions of each of said main wall structures are connected at suitable intervals by cross connecting reinforcing piers or stays 6, which may be cylindrical, or of any other suitable form, properly spaced and of sufficient number to effectually connect and brace the inner and outer walls, and so arranged as to avoid interference with the location and attachment of the several tube terminals, nipples and closing caps therefor, hereinafter described, and to facilitate free circulation of the water.

The ends of the side and end walls are connected by abutting one against the other, as shown in Fig. 3, their confronting walls or webs being joined by circulating nipples 80 a, c and b, c, establishing communication between the wall cavities. The front and back walls, and the circulating cavities thereof are connected by a plurality of water circulation tubes 7, the ends of which are 85 swaged or expanded in suitable receiving openings in the inner wall members 2, 2, as indicated at 8. The tubes are preferably arranged at an inclination from the rear wall to the front, of any desired slope or degree, 90 to facilitate circulation of the water being heated, and the terminals of the tubes are arranged in alinement with removable screw plugs or caps 9, whereby to facilitate the placing of the tubes and their connection 95 with the inner walls, and also to admit the entrance of a cleaning tool, if desired. The tubes are preferably arranged sufficiently far apart to provide intervening circulating spaces for the gases of combustion, the tubes 100 being preferably in staggered arrangement, as shown, in Fig. 1, and as will be readily understood.

At intervals throughout the height of the entire bank or series of tubes, I arrange a 105 plurality of alternating baffling headers 10, preferably in the form of cast metal boxes having parallel upper and lower walls extending entirely across the main interior boiler cavity from one side wall to the other, 110 said boxes having side and end walls which abut against the inner side section of the

main side walls, as shown in Fig. 1, and which, at their end portions, are connected with the circulating cavities *a*, *b*, by tube sections *7^a* and *7^b* respectively, and by comparatively short nipple sections *11*, expanded into the end wall of the boxes *10* and into the wall section *2*, in the same general manner as are the ends of the main tubes *7*, and in alignment with the plug openings above described. The inner ends of tube sections *7^a* may conveniently be threaded into the ends of the boxes *10*, as shown.

The lowermost header *10*, in the construction shown in Fig. 2, is provided with a downwardly extending hollow bridge wall terminal *10'* forming an extension of the hollow interior of the circulating baffling box, said downwardly extending portion being fixedly connected with the inner web of the side walls *C* by circulating nipples *11'*. For the purpose of providing a preliminary furnace chamber *D*, for green fuel, the lower end of the extension *10'* is connected by a series of somewhat closely adjacent water circulating tubes *12* with the inner member *2* of the front wall *8*, the tubes being threaded into the front wall of the extension *10'*, and expanded into the inner wall *2* of the front wall *A*, as shown.

By this construction, I provide a series of water circulating grate bars. The green fuel, as coal, may be charged through a door opening *13* having a door *14* in convenient location for firing. The main furnace or combustion chamber *E* is located immediately below the furnace chamber *D* above a series of grate bars *15*, either fixed or shaking, and above an ash pit *F*, firing openings *16* and doors *17* being provided for the chamber *E*, and the ash doors *18* closing the openings through the supporting frame or base *19*, providing access for the removal of ashes. Backwardly beyond the main combustion chamber *E* is a hollow bridge wall *20* extending upwardly above the level of the main grate bars *15*, below which is a partition *21* forming with the bridge wall *20* the rear wall of the main furnace chamber. A rear opening *22* and door *23* may be provided at the upper back portion of the base *19* for access to the interior, removal of dust, etc. It will be understood that the front, back and side walls are mounted upon and supported by the base *19*, being connected therewith by bolts or otherwise, as desired. An outlet for the products of combustion is provided through the wall *B* by means of a backwardly disposed outlet opening *24* formed by extending the walls *25* rearwardly from the main wall structure and connected with an outlet flue *26*, a controlling damper *27* being provided for control of the draft to the stack, as shown, or connection may be made for the stack in any other suitable manner. The rear and

front walls, except where interrupted by the door openings, are preferably covered by layers of asbestos, *28*, *29*. The front and back walls are also connected at the top by a series of water circulating tubes *30*, preferably of somewhat larger diameter than tubes *7*, the ends of which are swaged or expanded into receiving openings in the inner walls *2*, as shown, registering with corresponding openings in the outer wall *3*, closed by the plugs or caps *9*, above described. A layer of asbestos *31* is also laid over the top of tubes *30*, as shown, the several asbestos coverings thus completely covering the outer portion of the structure and providing effective heat insulation.

Water is supplied to the lower portion of the hollow rear wall *B* by a suitable supply connection *32*, and the heated water is carried off to the utilizing elements, as radiators, by a similar outlet conduit *33* connected with the upper portion of the main hollow front wall *A*, as clearly shown. It will be understood that the heated water may pass by circulation from the utilizing elements back to the supply conduit *32* for re-use in the ordinary practice.

By providing the preliminary combustion chamber *D* for the green fuel, in combination with the main combustion chamber *E*, the gases generated from the fuel in chamber *D* by the heat of combustion in chamber *E* will pass downwardly, as indicated by the arrows, and the gases in combustion will circulate backwardly through the opening between the header *10'* and bridge wall *20* upwardly and forward underneath the next adjacent header *10*, following the tortuous course effected by the several headers in a zig-zag direction and between the several water tubes, finally passing outwardly from the upper portion of the tube cavity to the stack and imparting the generated heat to the contained water in circulation through the tubes, headers and walls.

In the operation of the furnace, it will be understood that, in firing, portions of the partly gasified fuel on the water circulating grate bars *12* will be charged downwardly onto the main grate bars *15* in chamber *E*, and that, due to the preliminary coking action in chamber *D*, the generated gases, in combination with the usual air supply through the dampered doors *14*, *17* and *18*, will effect complete combustion, avoidance of smoke, and practically complete utilization of the fuel.

For the purpose of removing accumulations of ash, dust, etc., from the upper surfaces of the several headers *10*, I provide a series of openings *34* through the side walls *C* and within surrounding shell portions thereof extending transversely across the water circulating space *c*, said openings *34* being on the same level as the upper surfaces

of the heads 10 for the entrance of a suitable cleaning tool, the openings being closed by caps or doors 35 of any suitable construction. By this means access may be had to the interior for inspection at any time.

While I prefer to use the combined preliminary and main furnace chambers D and E, as above described, the successful operation of the invention is not necessarily dependent on such construction, as the boiler is well adapted to use with the ordinary single furnace or heating chamber, as illustrated in Fig. 4, depending upon the quality or kind of fuel being used. The construction, as shown in said figure, is otherwise substantially the same as that just described, the several parts being indicated by corresponding letters and numerals, the first baffling header 10 above main furnace chamber E being continuously flat like the other headers 10 and without the depending rear portion 10', the charging openings and doors 16, 17, being provided with the ash doors, grate bars, and other construction, as shown.

Where it is desired to utilize gaseous fuel, the grate bars may be eliminated and a suitable fuel gas burner 36 located at a suitable distance below the lowermost series of circulating tubes 7, the vertical space below such series of tubes being very considerably diminished, as clearly shown in Fig. 5. Such construction avoids the necessity of ash doors or ash receiving space, the circulation of the gases in combustion following the same course as that provided for in the use of solid fuel.

In the construction above described, the entire interior of the boiler is filled with circulating water. Where it is desired to utilize the construction for producing steam, I employ a steam drum 37 mounted in the upper portion of the boiler structure and supported upon and secured to the end walls and the inner edges of the side walls. For such purpose, the upper end portions of the end walls, and likewise the upper side portions of the side walls, are deflected inwardly, as indicated at 38, the water cavities a of the side walls being disposed inwardly toward the sides of the drum 37, just below its center, and these inner abutting ends of the side wall terminals are connected with the shell of the drum by circulating nipples 39 at each side, effecting communication between the water cavities of the side walls and the interior steam drum. Likewise, the upper end portions of the end walls A and B are provided with semi-cylindrical supporting depressions adapted to receive the end portions of the drum 37, the water circulation cavities a, b, being placed in circulating connection with the end portions of the drum by means of similar nipples 40 extending through the shell of the end walls and the shell of the

boiler, an intervening packing 41 of asbestos or other suitable material being preferably provided. The cavities a and b of the end walls are also placed in communication with the cavities C of the side walls by means of connecting nipples 42, providing for ample circulation. An outlet conduit 43 is connected with the drum 37 at any suitable point, as upwardly from the top thereof, for the purpose of making steam connection therewith.

It will be observed from the constructions shown and described that the entire boiler installation is of metal and is self-contained within the surrounding hollow circulating walls, in combination with the circulating tubes, headers, bridge wall, etc.

I avoid the necessity of any brick work whatever, and the boiler is thus capable of long continued use without deterioration or necessity of repair. It is capable of developing the full efficiency of the fuel and of maintaining a high or any desired degree of temperature in the water, the boiler is easily regulated and controlled, and is especially adapted to be used in connection with the installation of hot water heating systems.

It will be understood that the advantages of the invention may be embodied in boilers of various capacities or sizes or that the invention may be changed in detail features of construction, but that all such changes are to be considered as within the scope of the following claims.

What I claim is:

1. In a boiler of the class described, the combination of a supporting base, hollow cast side and end walls having hollow nipple connections, inclined water circulation tubes connecting the hollow front and back walls, water connections for the front and back walls, a plurality of hollow cast metal headers arranged in alinement with the tubes at alternating positions providing baffling walls for the gases of combustion and in circulating connection at each end with the end walls, and a combustion chamber provided with grate bars arranged below the lowermost of said headers, substantially as set forth.

2. In a boiler of the class described, the combination of hollow cast metal end walls and side walls, hollow nipples connecting said walls at the corners, a water supply connected to the base of one end wall, a water exhaust connected to the top of the other end wall, an outlet for the products of combustion, a furnace chamber at the lowermost inner portion of the boiler, a plurality of alternately arranged hollow cast metal circulating baffling headers connected at each end with the end walls by tubes, and a series of inclined water circulation tubes connecting the front and back walls, substantially as set forth.

3. In a boiler, a base structure, hollow cast metal side and end walls thereon inclosing a furnace chamber and having their end portions connected by circulating nipples, inclined water circulation tubes connecting opposite walls, a plurality of hollow cast metal headers arranged at varying alternating positions paralleling the water circulation tubes and communicating at each end with said opposite walls, the lowermost of said headers having a rear downward extension, and hollow water circulation grate bars connecting said extension with one of the end walls, substantially as set forth.
4. In a boiler, a base structure, hollow cast metal side, front and back walls thereon having their end portions connected for water circulation, a series of grate bars extending between the side walls and a hollow bridge wall in rear thereof connecting the side walls and providing with the grate bars a furnace chamber, inclined water circulation tubes connecting the front and back walls, a plurality of hollow alternating cast metal headers extending between the side walls and communicating at each end with the end walls, the lowermost of said headers having a rear downward extension, and a series of hollow grate bars connecting said extension with the front wall and arranged

over the first named grate bars, substantially as set forth.

5. In a boiler of the class described, rectangular cast metal side and end walls forming the main frame of the structure each having integral inner and outer side and endmost wall sections inclosing a hollow circulating interior, hollow water circulating tubes fixedly connected with the inner wall sections, the outer wall sections having registering openings and closing caps therefor, the upper portions of said end walls having their top portions formed to provide concave supporting depressions for a water and steam drum, a water and steam drum mounted thereon, hollow circulating nipples connecting said concave top portions with the shell of said drum to provide circulating communication with the interior thereof, the upper portions of the side walls being deflected inwardly and connected with the drum by similar nipples at each side thereof, a steam connection for said drum, and a water inlet connection for one of said end walls, substantially as set forth.

In testimony whereof I hereunto affix my signature in the presence of two witnesses.

FREDERICK J. FRENZ.
